(57) **CLAIM**

The ornamental design for a fob device, as shown and described.

DESCRIPTION

FIG. 1 is a front perspective view of a first embodiment of a fob device, such as an authentication token;

FIG. 2 is a front view thereof;

FIG. 3 is a back view thereof;

FIG. 4 is a left-side view thereof;

FIG. 5 is a right-side view thereof;

FIG. 6 is a top view thereof;

FIG. 7 is a bottom view thereof;

FIG. 8 is a first close-up perspective view thereof; and

FIG. 9 is a second close-up perspective view thereof.

FIG. 10 is a first close-up perspective view of a second embodiment of the fob device. The second embodiment includes a front perspective view, a front view, a back view, a left-side view, a right-side view, a top view (except the area shown with a dot-dash boundary line), and a bottom view that are identical to the corresponding views in the first embodiment; and,

FIG. 11 is a second close-up perspective view thereof.

The broken lines depict portions of the fob device that form no part of the claimed design. The dot-dashed broken lines represent boundaries of the claimed fob device and form no part of the claimed design.
